UNITED STATES PATENT OFFICE.

FREDERICK KLOTZ, OF READING, PENNSYLVANIA.

DESIGN FOR A GLASS FLYTRAP.

53,741.

Specification for Design.

Patented Aug. 26, 1919.

Application filed April 4, 1919. Serial No. 287,621. Term of patent 14 years.

To all whom it may concern:

Be it known that I, FREDERICK KLOTZ, a citizen of the United States, residing in the city of Reading, county of Berks, and State of Pennsylvania, have invented a new, original, and ornamental Design for a Glass Flytrap, of which the following is a specification, reference being had to the accompanying drawing, forming a part thereof.

In the drawing:—

Figure 1 is a side elevational view of a glass fly trap showing my design.

Fig. 2 is a plan view showing the under side of the design.

Fig. 3 is a central, sectional view of my design.

I claim:—

The ornamental design for a glass fly trap, as shown.

FREDERICK KLOTZ. [L.S.]
